FISHING TOOL

Filed March 21, 1927

UNITED STATES PATENT OFFICE

RALPH IRWIN HENDERSON, OF CHARLESTON, WEST VIRGINIA

FISHING TOOL

Application filed March 21, 1927. Serial No. 177,042.

This invention relates to a fishing tool of the type used in well drilling operations for the purpose of removing broken tools and other objects from wells. It is more especially an improvement upon the structure disclosed in my co-pending application filed September 24, 1926, Serial No. 137,547.

One of the objects of the invention is to provide a fishing tool utilizing grippers carried by the body portion of the tool, there being a plunger slidably mounted relative to the body and carrying a wedging element whereby, while the body is supported in normal position relative to the plunger while being lowered within a well, the grippers will be held spread apart until the descent is stopped by the obstruction in the path of the tool whereupon further downward movement of the spreading element will release the grippers for engagement with the object to be removed.

A further object is to provide grippers adapted to be operated independently of the wall of the casing in which the tool is lowered so that the said tool can thus be used in well casings of different diameters.

Another object is to provide means for automatically locking the body and plunger against relative movement after the grippers have been released upon reaching the obstruction, thus permitting withdrawal of the tool from the well without spreading the grippers.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a view partly in section and partly in elevation showing the parts of the fishing tool in their normal positions during the lowering of the tool.

Figure 2 is a side elevation of a portion of the tool.

Figure 3 is a section taken transversely through Figure 1 on the line indicated.

Referring to the figures by characters of reference 23 designates the body of the tool which can be cruciform in cross sectional contour as shown, or can be of any other preferred configuration. A central longitudinal bore 24 is provided within the body while longitudinal grooves 25 are formed in the outer surface of the body. Recesses 26 are located at the upper ends of the grooves and constitute seats for coiled springs 27 designed to thrust outwardly against the upper ends of levers 28 constituting grippers. These levers are fulcrumed within the grooves 25 as shown at 29 and extend any desired distances below the body 23, the lower ends of these levers or grippers being suitably shaped for proper engagement with a tool or other obstruction to be removed from a well. Extending inwardly from the grippers 28 below the body 23 are ears or projections 30 normally resting upon the periphery of the base 75 of a conical spreader 31. This spreader is located at the lower end of a plunger 32 slideable within the bore 24 and connected at its upper end to a suitable coupling or substitute 80 33 or other tool used in raising and lowering the structure. An annular groove 34 is formed in the upper portion of the plunger and is normally positioned above the body 23. A locking pin 35 is slideable within a radial bore 36 formed in the body and a spring 37 serves to thrust this pin against the plunger 32. The pin has a threaded socket 38 therein and a screw 39 is adapted to be inserted loosely into the bore and into threaded engagement with the pin after which, by 90

pulling on the screw the pin can be withdrawn from contact with the plunger.

As before pointed out the normal positions of the parts have been illustrated in Figure 1, the lower ends of the grippers being spread apart and being so held by contact of the projections 30 with the lower large end of the spreading tone 31. With the parts thus arranged the tool is lowered into the well, the weight of the body 23 and the parts carried thereby serving to maintain said parts against relative movement during the lowering action. When the obstruction or "job" is reached the grippers will arrive in positions at different points therearound and as further downward movement of the body and grippers ceases the plunger 32 will continue to move downwardly. Thus the grippers will be relieved from the spreading action of the frusto conical portion 31 and the springs 27 will act independently to shift the grippers so as to cause them to tightly engage and grip the object to be withdrawn irrespective of its cross sectional contour. During the completion of the downward movement of the plunger 32 relative to the body the pin 35 will snap into the groove 34. Thus the plunger and body will be fastened against relative movement and by pulling the tool upwardly the grippers will be held in contracted positions and continue to hold the article being withdrawn. After removal of the tool the key formed of the screw 39 can be placed in engagement with the pin 35 and used to pull the pin out of the groove 34 whereupon the plunger 32 can be pulled upwardly and the spreader 31 will shift the grippers away from each other.

Importance is attached to the fact that the grippers are held apart by the wedging action of the spreader 31 as long as the body 23 is supported solely by the plunger. Thus it is not necessary to use the fishing tool in a well casing of a predetermined diameter, as where frictional contact with the well casing is essential for the operation of the tool. Instead, with this form of tool, the same can be used in casings of all diameters with equal efficiency.

What is claimed is:

1. The combination with a plunger having a frusto conical spreader at its lower end, the large end of the spreader being lowermost, of a body slidably mounted on and supported by the plunger, spring pressed grippers pivotally connected to the body and extending therebelow, the base portion of the spreader constituting means for holding the grippers normally spaced apart, said plunger and spreader being movable downwardly relative to the body when the body is relieved of the support of the plunger, to release the grippers for independent movement toward each other under the action of their respective springs.

2. In a fishing tool a plunger, a frusto conical spreader at the lower end thereof, a body slidable on and adapted to be supported by the plunger, spring pressed grippers movably connected to the body, and adapted to engage and be held apart normally by the large end of the spreader while the body is supported by the plunger, said plunger and spreader being movable longitudinally relative to the body when unsupported by the plunger, to release the grippers for independent movement toward each other under the action of their springs, and means for automatically locking the plunger against upward movement relative to the body after the release of the grippers, said means including a normally restrained locking element movably mounted and a recess for receiving said element when the body and plunger are brought to predetermined relative positions.

3. A fishing tool including a body, a plunger slidable therein, a spreader at one end of the plunger, said plunger and spreader constituting means for supporting the body while being lowered for engagement with an object, grippers connected to the body and mounted for independent swinging movement, springs carried by the body for holding the grippers normally pressed against the spreader during the lowering of the body with the plunger, said spreader constituting means for holding the grippers normally spread apart, and being movable downwardly relative to the body when relieved of the support of the body, thereby to release the grippers for movement toward each other to grip an object therebetween.

4. A fishing tool including a body, a plunger slidable therein, a spreader at one end of the plunger, said plunger and spreader constituting means for supporting the body while being lowered for engagement with an object, grippers connected to the body and mounted for independent swinging movement, springs carried by the body for holding the grippers normally pressed against the spreader during the lowering of the body with the plunger, said spreader constituting means for holding the grippers normally spread apart, and being movable downwardly relative to the body when relieved of the support of the body, thereby to release the grippers for movement toward each other to grip an object therebetween, and cooperating means on the plunger and body for automatically locking them against relative movement when the grippers are released from the spreader.

5. A fishing tool including a body, a slideable plunger therein, a spreader on the plunger, said plunger and spreader constituting means for supporting the body while being lowered for engagement with an object, grippers movable with the body and mounted for

independent swinging movement, means movable with the body for holding the grippers normally pressed against the spreader while the body is being lowered with the plunger, said spreader constituting means for holding the grippers normally apart and being movable downwardly relative to the body to release the grippers for movement toward each other to grip an object therebetween.

5 10 In testimony that I claim the foregoing as my own, I have hereto affixed my signature.

RALPH IRWIN HENDERSON.
